OPENING AND CLOSING DEVICE

Gabriel Madland, Chicago, Ill., assignor to The
Youngstown Steel Door Company, Cleveland,
Ohio, a corporation of Ohio

Application October 18, 1935, Serial No. 45,632

4 Claims. (Cl. 268—44)

This invention relates to improvements in opening and closing device.

Railway house cars are customarily provided with doors slidably supported for controlling door openings formed in the side walls of such cars. The front vertical margin of these doors cooperates with vertical members to effect weatherproof construction for said margin in the closed position of the door. By reason of this cooperation a binding engagement between said front vertical margin and said members may occur, making it difficult at times to impart initial opening movement and final closing movement to said doors.

To overcome this difficulty devices known as door opening and closing or door operating devices are utilized. They comprise generally a lever which may be pivotally supported on a door and a link supported on a relatively fixed member with which the door is associated. The lever and link cooperate to impart the necessary movements to the door. The lever usually is pivoted so as to assume a vertical position, by far the greater portion of the lever depending below the pivot or fulcrum to obtain sufficient leverage in the operation of the device.

Such operating devices are conveniently located with respect to the ground and the lever may readily be grasped and effectively actuated from the ground. However, railway cars are more commonly loaded and unloaded at platforms provided for this purpose. The floors of these platforms are usually at the level of the floors of the railway cars. The sliding doors of these railway cars must, therefore, be opened and closed from the platform. The use of the door operating devices obviously becomes exceedingly awkward and the securing of the effective leverage of the lever is difficult.

It is, therefore, the primary object of this invention to provide a door opening and closing device for sliding doors capable of easy and effective operation both from the ground and from platforms. A further object is to provide door opening and closing devices for sliding doors embodying an actuating lever normally disposed in a vertical position, which device shall be capable of easy and efficient operation both from the ground and from loading and unloading platforms. A further object is the provision of door opening and closing devices for sliding doors embodying an actuating lever normally disposed in a vertical position in which the lever is capable of operation from the ground in one vertical position and capable of operation from a platform

when displaced through approximately 180° as effectively as from the ground. A further object is to provide door opening and closing devices for sliding doors embodying an actuating lever normally disposed in a vertical position and a co-operating link member wherein the lever when in its normal vertical position may be actuated from the ground to exert a substantially horizontal force on the link and, hence, on the door and when in substantially inverted position, may be actuated from a platform to again exert a substantially horizontal force on the link and the door with equal facility and effectiveness as from the ground. A further object is to provide a self-contained door opening and closing device for sliding doors capable of easy and effective operation, both from the ground and from platforms without requiring modification or additional means for this purpose. Other objects of the invention will become clear as the description thereof proceeds.

In the drawing forming part of this specification:

Fig. 1 is a fragmentary elevation of a pair of cooperating horizontal sliding doors for a railway house car to which an opening and closing device embodying the instant invention is applied, the device being illustrated in position for operation from a platform.

Fig. 2 is a view similar to Fig. 1 showing the device in position for operation from the ground.

Fig. 3 is a view similar to Fig. 2 showing the door in partially open position.

Fig. 4 is a vertical section taken on line 4—4 of Fig. 2.

Fig. 5 is a horizontal section taken on line 5—5 of Fig. 3.

Referring to the drawing which illustrates a preferred embodiment of the instant invention, there is disclosed a pair of cooperating sliding doors, the main door of which is designated by the numeral 10 and the auxiliary door by the numeral 11. The doors selected for the purpose of illustrating the invention are formed of metal. The main door 10 comprises a sheet metal panel 12 which is provided with spaced horizontal corrugations 13 and marginal vertical corrugations, one of which is indicated at 14 and into which the horizontal corrugations merge. The marginal portions of the metallic panel 12 are customarily reinforced by means of rigidifying members, one of such members 15 being illustrated in Figures 3 and 5 secured to the front vertical margin of the door.

The auxiliary door 11 is similarly provided with

a corrugated metallic panel 16, the horizontal corrugations of which are indicated at 17 and one of the vertical corrugations being indicated at 18. The front vertical rigidifying member of the auxiliary door is shown at 19, this member cooperating with a jamb or post 20 fastened to said margin of the auxiliary door to provide a pocket 21 for the reception of the front vertical margin of the main door when the doors are in closed position.

10 In this position of the main and auxiliary doors a binding frequently occurs between the front vertical margins of the doors making it difficult to impart initial opening movement to the main door and final closing movement thereto. It is to be understood that in the closing of the doors the auxiliary door is first brought to its closed position and the main door is then closed. In order, effectively, to overcome this binding action the opening and closing device of the instant invention is utilized, said device being so designed as to be capable of imparting initial opening movement and final closing movement to the main door with equal facility both from the ground and from a loading platform.

25 The construction of the opening and closing device is such that it utilizes a portion of the door locking means. This locking means comprises a hasp fastener 22 secured preferably upon a horizontal corrugation 13 of the main door 10. Rivets 23 are preferably utilized for this securing, these rivets passing through a backing member 24 disposed within the horizontal corrugation upon which the hasp fastener is positioned. The hasp fastener 22 embodies a neck portion 25, the free end 26 of which passes through the eye of a hasp 27 and through the metallic panel 12 and the adjacent end of the backing member 24. The hasp 27 is thus swingably fastened upon the main door 10 and in order to lock the main and auxiliary doors together is provided with an abutment 28 cooperating with a tapered locking pin 29 secured upon the auxiliary door 11 for vertical movement. The securing of the locking pin 29 is effected by means of a lock plate 30 riveted to the panel 16 of the auxiliary door as indicated at 31, and provided with housing members 32 and 33 within which the locking pin is received. Means not vital to the instant invention is employed to prevent disengagement and loss of the locking pin from the lock plate 30.

30 The instant embodiment of the invention utilizes the hasp 27 as a part of the door opening and closing device. This device embodies, additionally, an operating lever 34 which preferably is pivotally mounted upon the lock plate 30 for swinging movement in a plane parallel to the plane of the auxiliary door. This pivotal securing of the operating lever upon the locking plate member is effected by means of a hollow boss 35 preferably formed as an integral portion of the lock plate member which extends through an elongated longitudinal slot 36 formed adjacent 35 one end of the operating lever. Disengagement of the lever from the boss 35 is prevented by means of a washer 37 larger than the slot 36 and secured to the boss by means of a rivet 38 passing therethrough. The operating lever 34 carries lugs 39 and 40 which are disposed on opposite sides of and adjacent the slot 36. The lugs 39 and 40 are provided respectively with lip portions 41 and 42 by means of which an interlocking engagement between said lugs and the portion of the hasp 27 adjacent an opening 43 provided therein and

through which each of the lugs is adapted to extend may be had.

5 It has been stated hereinabove that the opening and closing device embodying the instant invention is effective in performing its intended function as fully when operated from a platform as when operated from the ground. The operation of the opening and closing device from the ground in order to impart initial opening movement to the door is illustrated in Figs. 2 and 3 10 of the drawing. In Fig. 2 the doors are shown in their fully closed position. In order to impart initial opening movement to the main door 10 the association between the operating lever 34 and the hasp 27 will be as indicated in Fig. 2 15 of the drawing. As shown, the operating lever 34 lies behind the hasp 27 and the lug 40 provided on the operating lever extends through the opening 43 formed adjacent the free end of the hasp. The locking pin 29 is first raised so as to become 20 disengaged from the lug or abutment 28 provided on the hasp. The lower end of the operating lever 34, which constitutes the handle end, is then grasped and a force exerted thereon in the direction of the opening movement of the main door. 25 This force will be transmitted by virtue of the cooperation between the lug 40 and the hasp to the hasp and through the hasp to the main door 10 which will then move away from the auxiliary door. The position of the various parts of the 30 construction when the door has been given an initial opening movement by the operation of the opening and closing device is clearly shown in Fig. 3 of the drawing. The hasp 27 may then be released from the lug 40 of the operating lever 35 and the main door 10 readily moved to its full open position if desired.

35 Should the need for imparting initial opening movement to the main door arise when the car provided with said door is disposed at a loading platform, the opening and closing device of the instant invention may be used as effectively as hereinabove described. For this purpose the lug 40 of the operating lever is released from the hasp 27 and the lever is then turned in a clockwise direction so that it assumes an inverted 40 position. In this position of the lever the lug 39 is extended through the opening 43 provided in the hasp so as to effect engagement between said lug and said hasp. When the locking pin 29 45 has been raised to the position shown in Fig. 3 of the drawing, the handle end of the operating lever may be grasped and a force exerted upon the lever tending to turn it in a counter-clockwise direction, as viewed in Fig. 1 of the drawing. 50 The lug 39 will then exert a force upon the hasp 27, which force will be transmitted to the main door and effect initial opening movement thereof. It is apparent that in the inverted position of the operating lever 34 as great a force may be as 55 effectively exerted to obtain initial opening movement of the main door as when the operating lever is actuated in its normal position from the ground.

60 It will be apparent without further detailed explanation that the operating lever will cooperate with the hasp in the normal and inverted positions of said lever to obtain final closing movement of the main door 10. Attention is also invited to the fact that in both the normal and inverted positions of the operating lever it will exert a substantially horizontal force upon the hasp 27 so that all of said force is utilized for the purpose of opening or closing the main door.

65 The opening and closing device illustrated is 75

shown applied to the two doors of a railway house car commonly utilized to control a large door opening provided in a side of such car. Where a smaller opening is satisfactory, a single door will be utilized to control such opening and it is to be understood that the instant invention is as readily applicable to single door house car constructions as to the double door construction illustrated. It will be apparent, moreover, that the 5 positions of the hasp fastener and hasp and of the lock plate and operating lever may be reversed; that is, the hasp fastener or hasp may be fastened to the auxiliary door or to a car side and the lock plate and operating lever may be 10 fastened to the main door or to the single door of a railway house car.

It will be apparent that numerous changes and modifications in the details of the invention will be clear to those skilled in the art. It is intended, 15 therefore, that all such modifications and changes be comprehended within this invention, which is to be limited only by the scope of the claims appended hereto.

I claim:

25 1. A door opening and closing device comprising a lever adapted to be pivotally suspended from a relatively stationary member for swinging movement in a vertical plane and cooperating means adapted to be swingably mounted upon a 30 sliding door associated with said member, lugs provided on said lever on opposite sides of the lever pivot, one of said lugs being capable in suspended position of said lever of association with said means in the substantially horizontal 35 position thereof to impose substantially horizontal oppositely directed forces thereon and the other of said lugs being capable in the substantially inverted position of said lever of association with said means in the substantially horizontal 40 position thereof to impose substantially horizontal oppositely directed forces thereon.

2. A door opening and closing device comprising a lever, a slot formed in said lever adjacent one end thereof, said lever being adapted to be 45 swingably and slidably suspended from a boss extending through said slot and carried by a relatively stationary member, lugs provided on said lever adjacent to and on opposite sides of said slot and means cooperable with said lever adapted

to be swingably mounted upon a sliding door associated with said member, one of said lugs being capable in the suspended position of said lever of association with said means in the substantially horizontal position thereof to impose substantially horizontal oppositely directed forces on said means. 5

3. In a railway house car having a sliding door member and a relatively stationary member associated therewith, a lever pivotally mounted on one of said members for swinging movement in a plane substantially parallel to said member, means pivotally mounted on the other of said members, said lever and said means cooperating to impart opening and closing movements to said door member, said lever in one vertical position being engaged with said means and operated from the ground to impart both opening and closing movements to said door member, said lever in inverted position being engaged with said means and operated from a loading platform to impart both opening and closing movements to said door member, the position of said means when in engagement with said lever being substantially the same for both positions of the lever. 10 15 20 25 30

4. In a railway house car having a sliding door member and a relatively stationary member associated therewith, a lever mounted upon one of said members for swinging movement in a plane substantially parallel to said member, means 35 mounted for swinging movement upon the other of said members, said lever when in a vertical position being releasably engaged with said means in the substantially horizontal position thereof to impart horizontal opening and closing 40 forces to said door member, said lever when released from said means being swingable to substantially inverted position, said lever when in said inverted position being releasably engaged with said means in the substantially horizontal 45 position thereof to again impart horizontal opening and closing forces to said door member.

GABRIEL MADLAND.
